DETACHABLE BRIDGE-BRACE-BAR
SPECTACLE CONSTRUCTION

Frederick A. Stevens, Providence, R. I.

Application January 23, 1946, Serial No. 642,890

1 Claim. (Cl. 88—41)

1

This invention relates to an ophthalmic mounting and more particularly to the mounting of a high arm at the nasal edge of a lens.

In the mounting of a high arm in a spectacle, usually the fastening member which holds the lens in position at the bridge or nasal edge of the lens passes through this high arm for securing one end of it in position. In such a mounting the arm may move pivotally with such securing means, for instance when the high arm is bent there is a tendency to move the securing means. Further, because the high arm serves at its opposite end as a connection for the temple, it is necessary that the temple end remain substantially in a fixed position with relation to the lens, and it is considered necessary to also fix the temple end of the high arm.

One of the objects of this invention is to provide a construction which will secure the nasal or bridge end of the high arm in such a manner that it will be unnecessary to secure the temple end of the high arm to the lens.

Another object of this invention is to provide a securing of the nasal or bridge end of the high arm so as to leave the high arm free to be bent without moving or changing the securing means in any manner.

Another object of this invention is to mount the nasal or bridge end of the high arm so that it cannot rotate or swing with or about the securing pin as a pivotal point.

Another object of this invention is to so arrange the binding of the lens in position by means of a strap that the high arm and lens strap will be bound by one and the same member for securely binding the entire assembly in position.

Another object of this invention is to provide a binding arrangement so that there is no chance of loosening the securing screw by movement of the high arm.

With these and other objects in view, the invention consists of certain novel features of construction, as will be more fully described and particularly pointed out in the appended claim.

In the accompanying drawings:

Fig. 1 is a front elevation of the spectacle equipped with this invention;

Fig. 2 is a top plan view thereof showing the temples broken away;

Fig. 3 is a section on line 3—3 of Fig. 1;

Fig. 4 is a sectional view similar to Fig. 3 but showing the parts in exploded relation so that they may individually better be seen;

Fig. 5 is a rear view of one of the lenses with

its bridge strap and high arm mounted in position;

Fig. 6 is a perspective view showing a fragmental portion of the lens, the strap, and the high arm in separated but adjacent relation indicating the relative positions of these parts;

Fig. 7 is a sectional view similar to Fig. 4 of a modified construction; and

Fig. 8 is an edge view of the strap shown in Fig. 7.

In proceeding with this invention, I provide a strap for a lens which will have ears in spaced relation to receive the lens between them. One ear of the strap is thinned or omitted and a high arm which is to be mounted has an ear to extend along this thinned ear to the strap or replaces such ear. Openings to extend through the strap arms, the lens, and the portion of the high arm which extends along one strap arm are in registry to receive a bolt or threaded pin to hold the parts assembled and in order to prevent swinging of the high arm with or about this pin, a projection on the high arm enters a recess in one ear along which it extends so as to provide a two point connection and thus prevent swinging about the pin as an axis.

With reference to the drawings, 10, 10 designates the lenses. On the inner nasal or bridge edge of each of these lenses, there is provided a strap designated 11. This strap has the usual ear 12 and a thinned ear at the back thereof designated 13, these ears being connected together by a shoe portion 15 which has arms 16 and 17 to extend along and engage the inner edge of the lenses 10. A bridge 18 extends between the straps and is joined to this shoe 15 and from adjacent the ends of the bridge at its junction with the shoe there extend bendable arms 19 which support nose pads 20.

A high arm designated generally 21 is provided at its inner nasal or bridge end with an ear 22 which is broadened out with relation to the wire forming the general extent of the arm 21 so as to lay along the thinned ear 13 of the strap.

This arm is provided with an opening 23 which is threaded. The lens 10 is also provided with a hole 24 and a bolt or threaded pin 25 extends through the holes in the ears 12 and 13 and the hole 24 in the lens. The threaded end 26 of this pin 25 enters the threaded opening 23 in this ear 22 of the high arm. A head 27 of the bolt fits into a recess 28 in the arm 12 and this head is slotted as at 29 so that it may be entered by means of a screw driver for rotating the same.

In order to prevent rotation of the high arm

21 with or about the pin 25 as a center I provide a recess 30 in the ear 13 and a projection 31 on the ear 22 enters this recess. This recess may be so located that the projection 31 extends into the space between the ears 12 and 13 and in this case a recess or notch 32 is also provided in the edge of the lens 10 so that when the lens is in position the notch 32 and recess 30 will align for the reception of the projection 31.

By this means of mounting the high arm in position, the ear end at the bridge or nasal edge will be maintained firmly in position and bending of the long arm 21 may be had without danger of releasing or loosening the bolt or pin 25. This bending may serve to cause the high arm 21 to follow the contour of the lens 10 and also to properly position the spaced ears 33 and 34 for mounting the temples 35 in position in the assembly of the spectacle.

In the modified form shown in Figs. 7 and 8, the strap 36 has an ear 12' to engage the front of the lens and a shoe 15' to engage the edge thereof. In this shoe is a notch 30' of a size to wholly contain the pin 31 of the high arm. A bulge in the shoe as at 37 may be necessary for this purpose. By this arrangement, the edge of the lens need not be notched such as at 32 as shown in the other figures.

I claim:

In an ophthalmic mounting a bridge having a lens strap with an ear to extend along a face of a lens, said ear having a hole therein and in addition an opening extending therethrough, a lens having a hole to register with said hole in said ear and a recess in its edge to register with said opening, a high arm designed to extend along the top edge of the lens and having a support at one end with a projection to extend into said opening and recess and also having a hole to register with said holes and a securing member to extend into said holes to hold the lens strap and high arm assembled with the lens.

FREDERICK A. STEVENS.
